SCAFFOLD

Claude H. Adams, Glens Falls, N. Y.

Application July 28, 1931. Serial No. 553,488

3 Claims. (Cl. 304—29)

My invention more particularly relates to a scaffold which is of simple construction and which may readily be raised or lowered from beneath the working scaffold, and which may readily be supported in any desired position on suitable columns.

Another object of my invention is the provision of a foot scaffold supported from the working scaffold so that the entire scaffold may be raised and lowered as a unit.

Another object of my invention is the provision of needle beams for the scaffolding which are forked at their ends and embrace the columns and engage and are supported by pins which are received in spaced openings in the columns.

My invention will best be understood by reference to the accompanying drawing in which I have illustrated a preferred embodiment thereof and in which Fig. 1 is a side view of a fragmentary portion of a column and one end of a scaffold supported thereby; Fig. 2 is a fragmentary end view of a portion of Fig. 1; Fig. 3 is a fragmentary plan view of one end of one of the needle beams. Fig. 4 is a perspective view illustrating a plurality of columns and the scaffold supported thereby, and Fig. 5 is a perspective view illustrating a modified form of jack support.

Like reference characters indicate like parts throughout the drawing.

Referring now to the drawing, 10 indicates supporting columns provided with openings 11 which preferably extend transversely through the columns and in which are received pins 12 which extend well beyond the columns as indicated in Fig. 2.

Needle beams 13 are forked at their ends, as indicated in Fig. 3, and may conveniently be formed of three strips, a comparatively short strip 131 which is substantially the same width as the associated column, and two longer strips 132 which embrace the column and engage and are supported on the ends of the pins 12. The strips 131 and 132 may conveniently be secured together by suitable clamping bolts 14 (see Fig. 3).

In the embodiment of my invention illustrated, the needle beams are raised by suitable jacks, indicated generally at 15, which rest upon jack supporting members indicated generally at 16 provided with arms 17 which embrace opposite sides of the columns 10 and are provided with notches 18 which engage other pins 121 in other openings. The bottom portion of the member 16 is also provided with laterally extending arms 181 which also embrace the columns 10. The member 16 is provided at its upper portion with

a bracket 19 on which the base portion 151 of the jack is supported, a block 191 preferably being interposed between the bracket and the base of the jack. The bracket 19 and the block 191 are provided with holes to receive the lower end of the 60 jack screw. A suitable block 20 may also be interposed between the upper portion of the jack and the needle beam 13.

The foot scaffold, on which the operator stands, preferably comprises beams 21 which may be 65 the same structurally, as the needle beams 13 but usually of lighter construction, and are provided with pins 22 by which they may be suspended by cables 23 which engage suitable pins 24 in the working scaffold. Planks or boards 25 are also 70 laid upon the beams 21.

By operating the jack, the entire scaffold, including the working scaffold and the foot scaffold, are raised as a unit by the operator from beneath the working scaffold. When the working scaffold has been elevated to the desired position, the pins 12 are inserted through openings 11 beneath the needle beams and the working scaffold is thus conveniently held in its adjusted 75 position.

In the embodiment of my invention illustrated in Fig. 5, I have illustrated a modified form of supporting jack comprising a block 26 which is of substantially the same width as the column on which it is to be supported and to the sides of which are secured arms 27 which embrace column 10, the arms 27 being provided with holes 28 through which pins may be inserted and which extend through openings 11 in the columns.

Assuming that the scaffold embodied in my invention is used for the purpose of building a wall, then when the wall reaches a height where the masonry can no longer conveniently be laid, the working platform is placed in position by placing the forked ends of the needle beams 13 over associated adjacent columns, and pins inserted beneath the needle beams to hold the same in position at the desired height. The platform 30 is then laid upon the needle beams. When it is desired to raise the working platform, the operator while standing beneath the working scaffold places the jack supporting member 16 in position on the column 10, the arms 17 engaging the ends of pins 121. The jack 15 is then placed in position between the jack support and the end of a needle beam, it being understood that a similar jack is preferably placed at the opposite side of the scaffold beneath the opposite ends of the needle beam. The operator then 100 raises the needle beam to the desired position 11

and places pins 12 in the openings 11 beneath the beam and on which it is then supported. The jacks and the jack supporting members may then, if desired, be carried to other parts of the scaffold for raising other parts thereof.

When the working scaffold has reached a height where it is inconvenient for the operator to actuate the jacks from the ground, the foot scaffold is suspended from the working scaffold 10 by means of the cables 23 and then, by standing on the foot scaffold, the operator can raise both the working scaffold and the foot scaffold as a unit.

By forming the needle beams with forked ends, 15 which embrace the associated columns, there is no possibility of the needle beams being dislodged from the supporting columns.

While I have described my invention in its preferred embodiment, it is to be understood that 20 the words which I have used are words of description rather than of limitation and that the drawing is merely illustrative. Hence, changes within the purview of the appended claims may be made without departing from the true scope and 25 spirit of my invention.

What I claim is:

1. In a device of the character described, a plurality of columns each provided with transversely extending spaced openings, supporting pins re-

ceived in said openings, a needle beam engaging and supported by pins in said openings, a jack support, means for supporting the same on a pin in another opening, and a jack mounted on said support and engageable with said needle beam.

80

2. In a device of the character described, a plurality of columns each provided with transversely extending spaced openings, supporting pins received in said openings, needle beams the ends of which are forked and adapted to embrace a column and be supported by the ends of pins located in said openings, a jack support comprising members extending on opposite sides of the associated columns and engageable with and supported by another pin in another opening and a jack mounted on said support and engageable with a needle beam.

85

3. In a device of the character described, a plurality of columns each provided with transversely extending spaced openings, supporting pins received in said openings, needle beams the ends of which are forked and adapted to embrace spaced columns and engage and be supported by pins extending through said openings, a jack support, means for supporting the same on a pin in another opening, a jack mounted on said support and engageable with a needle beam and a foot scaffold suspended from said beams.
